UNITED STATES PATENT OFFICE.

JOHN E. BITTING, OF LOS ANGELES, CALIFORNIA.

POST PRESERVER.

1,419,108.

Specification of Letters Patent. Patented June 6, 1922.

Application filed January 11, 1921. Serial No. 436,496.

To all whom it may concern:

Be it known that I, JOHN E. BITTING, a citizen of the United States, residing at Los Angeles, in the county of Los Angeles and

5 State of California, have invented new and useful Improvements in Post Preservers, of which the following is a specification.

It is the object of this invention to provide means for preserving wooden posts and the 10 like, such as telegraph poles.

The invention provides a casing adapted to receive the end of the post, which is inserted in the ground, and which is so arranged as to rigidly support the post while

15 permitting the saturation of the end of the post which is inserted in the ground with a suitable preservative.

The invention will be readily understood from the following description of the accompanying drawings, in which:

20 Figure 1 is a side elevation of a post having the improved preserving means employed in connection therewith, and shown in longitudinal section.

25 Figs. 2 and 3 are transverse sections on the lines 2-2 and 3-3 of Figure 1.

The post in connection with which the preserving means is employed is shown at 1, and may be a telegraph pole, fence post or 30 the like. The lower end thereof, which is received in the ground, is tapered downwardly as shown at 2.

A casing 3, preferably, of metal is received over the tapering end 2 of the post, 35 and said casing preferably tapers downwardly, so that it may be readily inserted in the ground. At its lower end it is provided with an annular flange 4 for retaining the casing in position when the earth E is

40 packed around the same. Longitudinally extending ribs 5 are preferably also provided on the outside of the casing for preventing turning of said casing in the earth.

The wall of casing 3 is radially spaced 45 from the end 2 of the post received therein, and radial ribs 6, which are circumferentially spaced as shown at 7, extend inwardly from casing 3, so as to define a central downwardly tapering bore 8 into which the tapering end of the post is wedged.

The upper end of casing 3, preferably, extends above the surface of the earth, and terminates in an end cap 9, which is provided with an axially inwardly extending 55 frame 10 extending to the ends of ribs 6, which preferably terminate short of the top

of the casing. By this arrangement an annular space 11 is provided at the top of the casing communicating with the spaces 7 between the ribs 6.

After the casing has been positioned in the ground, and the pole has been inserted therein, the latter is preferably sealed in position by providing a groove 12 around the axial bore provided in end plate 9, and filling said groove with plastic material such as cement. A filling plug 13 is provided in end plate 9 by means of which a suitable preserving liquid, such as creosote, may be supplied to spaces 7 and 11.

The construction as thus described provides a rigid support for a post in casing 3 by the wedging engagement of the tapering end of the post in the tapering bore 8, and at the same time a preserving material is maintained in intimate contact with the post, so as to prevent rotting of the latter. When the post is thus mounted in position within its casing, an airtight construction is also provided, which will prevent deterioration 80 of the post from atmospheric influences.

Various changes may be made without departing from the spirit of the invention as claimed.

What is claimed is:

1. A preserving casing having inwardly extending radial ribs forming an axial tapering bore, and an end plate on said casing having an axial inwardly extending flange extending to the ends of said ribs, the spaces 90 between said ribs, and the space between said flange and said casing communicating with the same, being adapted to contain a preservative.

2. A preserving casing having inwardly extending radial ribs forming an axial tapering bore communicating with the spaces between said ribs, and an end plate upon said casing having an axial inwardly extending flange forming a prolongation of said axial bore and extending to the ends of said ribs, the spaces between said ribs, and the spaces between said flange and said casing, communicating with the same, being adapted to contain a preservative.

3. A post preserving casing having inwardly extending radial ribs defining an axial bore that is adapted to receive the lower portion of a post, the chambers between said ribs being adapted to receive a preservative, 110 the top of said casing being provided with an end plate in which is formed a centrally

arranged opening, and there being a groove formed in the top of said plate and concentrically arranged around the opening therein, which groove is adapted to receive a 5 sealing compound.

4. A post preserving casing having inwardly extending radial ribs forming an axial bore that is adapted to receive the lower portion of a post, the chambers between said 10 ribs being adapted to receive a liquid preservative, an end plate formed integral with

the upper end of said casing, which end plate is provided with a centrally arranged opening, a frame extending downwardly from said end plate around the opening 15 therein, and there being a channel formed in the top of the plate and disposed about the opening therein, which channel is adapted to receive plastic material.

In testimony whereof I have signed my 20 name to this specification.

JOHN E. BITTING.
